UNITED STATES PATENT OFFICE.

LOUIE W. SMITH, OF DES MOINES, IOWA.

WRENCH.

1,204,515.

Specification of Letters Patent.

Patented Nov. 14, 1916.

Application filed March 22, 1916. Serial No. 85,918.

To all whom it may concern:

Be it known that I, LOUIE W. SMITH, a citizen of the United States, residing at Des Moines, in the county of Polk and State of Iowa, have invented certain new and useful Improvements in Wrenches; and I do hereby declare the following to be a full, clear, and exact description of the invention, such as will enable others skilled in the art to 10 which it appertains to make and use the same.

This invention relates to new and useful improvements in wrenches and the principal object of the invention is to provide a wrench 15 which is adapted for quick adjustment, and which when adjusted will be held against possible movement.

A further object of the invention is to provide a wrench which may be simply constructed and will be easily operated.

With these and further objects in view, the invention consists in the novel combination and arrangement of parts which will be fully set forth in the following specification and accompanying drawing, in which:—

Figure 1 is a longitudinal sectional view through a wrench constructed in accordance with this invention, Fig. 2 is a transverse sectional view on the line 2—2 of Fig. 1, 30 Fig. 3 is a transverse sectional view on the line 3—3 of Fig. 1, Fig. 4 is a view similar to Fig. 1 of the modified form of my invention and Fig. 5 is a transverse sectional view through the modification taken on the line 35 5—5 of Fig. 4.

Referring to the drawing the numeral 1 designates a shank of a wrench provided with a plurality of notches 2 which form a plurality of teeth 3 as clearly shown in the 40 drawing. A suitable head 4 is formed at one end of the shank and provides a wrench jaw while the opposite end of the shank is provided with a reduced cylindrical extension 5 having a reduced threaded extension 6 formed thereon. The shank 1 is preferably rectangular in cross section as illustrated in Figs. 2 and 3 and slidably mounted thereon is a head 7 forming a movable jaw member which is provided with the central rectangular opening 8 for the reception of the shank and the internally screw-threaded sleeve 9, the inner wall of which is spaced outwardly from the shank as clearly shown in the drawing. A pawl 10 is pivoted in a recess 11 formed in the sleeve 9 at the point where the same joins the head 7 and this

pawl is adapted for engagement with the teeth 3 hereinbefore referred to so as to rigidly hold the jaw against accidental movement.

In order to provide an adjusting means for the jaw, a suitable handle 12 is provided and is formed with an inwardly extending flange 13 at one end which is adapted to engage in the space between the wall formed by the cylindrical portion 5 and the nut 14 which is threaded on the extension 6 so that the handle will be held against longitudinal movement with relation to the shank. It will also be noted however that the handle 70 may be rotated with relation to the shank and is provided at the end opposite the flange 13 with the externally screw-threaded cylindrical extension 15 which is adapted to engage the threads on the inner space of the 75 sleeve 9 so that upon rotation of the shank the sleeve 9 and head 7 will be adjusted relatively to the shank and head 4.

Referring to the modified form of the invention as illustrated in Fig. 4 the numeral 80 16 designates the shank of the wrench which corresponds with the shank 1 of the wrench previously referred to and this shank 16 is provided with a plurality of notches 17 forming space teeth in connection with which 85 the pivoted pawl 18 carried in the recess 19 of the sleeve 20 coöperate. The shank 16 and sleeve 20 each carry suitable jaw members 21 which are adapted to be adjusted with relation to each other by the movement of the 90 sleeve on the shank. The end of the shank opposite the jaw member like the end of the shank 1 is provided with a cylindrical extension 22 and a similar reduced threaded extension 23 on which the nut 24 is threaded, 95 the space between the nut and the end of the shank forms an angular groove in which the flange 25 of the handle 26 is rotatably mounted. The handle is formed with suitable internal screw-threads which coöperate 100 with screw-threads on the exterior of the sleeve 20 and it can thus be seen that when the handle is rotated the sleeve will be adjusted on the shank.

It will be apparent from the foregoing 105 that in use the wrench is adjusted by the user pressing upon the lever for releasing the catch 10 or 18 and then upon rotating the handle it will be apparent that the jaw may be adjusted to the proper place whereupon the user releases the catch and allows the pawl to drop into one of the recesses 110

thereby firmly locking the jaw against movement.

While in the foregoing there has been shown and described the preferred embodiment of this invention, it is to be understood that such changes may be made in the combination and arrangement of parts as will fall within the spirit and scope of the appended claim.

10 What I claim is:—

A wrench including a shank, a sleeve slideable on said shank, a jaw member mounted at one end of the shank, a jaw member on the sleeve adapted to coöperate with the jaw member on the shank, a plurality of teeth

on the shank, a latch adapted to engage the teeth to hold the jaw member in various adjusted positions on the shank, a handle rotatable on the shank, means to hold the handle against longitudinal movement with relation to the shank, and means connecting the handle with the sleeve whereby when the sleeve is rotated the jaw member will be adjusted.

20 In testimony whereof I affix my signature in presence of two witnesses.

LOUIE W. SMITH.
